INSULATED JUG

Walter E. Moore, St. Louis, Mo., assignor to Knapp-Monarch Company, St. Louis, Mo., a corporation of Delaware

Filed Dec. 19, 1955, Ser. No. 39,363

Term of patent 14 years

(Cl. D58—17)

Figure 1 is a top plan view of an insulated jug showing my new design;

Figure 2 is a side elevation view of the same taken looking from the right of Figure 1; and

Figure 3 is another side elevation view of the same taken looking from the left of Figure 2.

The dominant feature of my design resides in the portions shown in full lines on the drawings.

I claim:

The ornamental design for an insulated jug, substantially as shown and described.
